(57) **CLAIM**

We claim the ornamental design for a gas detection device, as shown and described.

DESCRIPTION

FIG. 1 is a top, front, and right perspective view of a gas detection device showing our new design;
FIG. 2 is a front elevational view thereof;
FIG. 3 is a rear elevational view thereof;
FIG. 4 is a left side view thereof;
FIG. 5 is a right side view thereof;
FIG. 6 is a top plan view thereof; and,
FIG. 7 is a bottom plan view.

The broken lines in the drawings illustrate portions of the gas detection device which form no part of the claimed design.

The dot-dashed line in the drawings defines the boundary of claimed design and forms no part of the claimed design.
